(57) **CLAIM**

I claim an ornamental design for a bicycle light housing, as shown and described.

DESCRIPTION

FIG. 1 is an upper right top isometric view of the bicycle light housing;

FIG. 2 is a right bottom isometric view of the bicycle light housing;

FIG. 3 is a left top isometric view of the bicycle light housing;

FIG. 4 is a left bottom isometric view of the bicycle light housing;

FIG. 5 is a front elevational view of the bicycle light housing;

FIG. 6 is a back elevational view of the bicycle light housing;

FIG. 7 is a left side elevational view of the bicycle light housing;

FIG. 8 is a right side elevational view of the bicycle light housing; and

FIG. 9 is a top plan view of the bicycle light housing; and, FIG. 10 is a bottom plan view of the bicycle light housing. The broken-line disclosures, as shown through the FIGS. 1-10, are understood to represent portions of the article in which the claimed design may be embodied, but which form no part of the claimed design.
